UNITED STATES PATENT OFFICE.

JOHN W. BROAS, OF ALBION, MICHIGAN.

DESIGN FOR A WRENCH-JAW.

SPECIFICATION forming part of Design No. 31,486, dated September 5, 1899.

Application filed October 22, 1897. Serial No. 656,109. Term of patent 7 years.

To all whom it may concern:

Be it known that I, JOHN W. BROAS, residing at Albion, in the county of Calhoun, in the State of Michigan, have invented and produced a new and original Design for Wrench-Jaws, of which the following is a specification, reference being had to the accompanying drawing, forming a part thereof.

The invention is illustrated in the accompanying drawing, which presents a detail perspective view of a wrench-jaw constructed in accordance with my design.

As shown in the drawing, the leading or material features of my design consist of a body portion which is substantially square in outline and open at top and bottom and an upright portion substantially at right angles to the body portion. The inner face of the upright portion of the jaw gradually angles

inwardly the greater portion of its length and outwardly quite abruptly above the point where it joins the body portion, so that the upright portion is wider at the upper end. The inner face of the upright portion has a groove, the sides of which diverge slightly toward the bottom and converge slightly toward its upper end, extending lengthwise of the same.

Having described my invention, what I claim as new, and desire to secure by Letters Patent, is—

The design for a wrench-jaw substantially as herein shown and described.

JOHN W. BROAS.
